A. PETZOLD..

RUG.

No. 17,175.

Patented Mar. 8, 1887.

UNITED STATES PATENT OFFICE.

ADOLPH PETZOLD, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 17,175, dated March 8, 1887.

Application filed January 15, 1887. Serial No. 224,491. Term of patent 3½ years.

To all whom it may concern:

Be it known that I, ADOLPH PETZOLD, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such person to use my invention.

The leading features of my design consist in an ornamental floral border at top and bottom, as shown, at each end floral cross-borders showing different floral representations from the top and bottom borders, the center in form of a panel upon which is a floral representation on a light background in the center and a dark background at each end, the larger masses of flowers being at the extremities and the smaller ones in the central portions of the panel, as shown.

What I claim as my invention is—

The design for a rug, consisting of ornamental top and bottom borders, as shown, and floral cross-borders, as shown, and ornamental floral center panel, the larger masses of flowers being at the extremities and the smaller ones in the central portions of the panel, all as shown in the photographic print.

ADOLPH PETZOLD.
